(57) **CLAIM**

The ornamental design for an ultrasound transducer, as shown and described.

DESCRIPTION

FIG. 1 is a top-front-left perspective view of an ultrasound transducer showing my new design;
FIG. 2 is a bottom-front-left perspective view thereof;
FIG. 3 is a top-rear-right perspective view thereof;
FIG. 4 is a bottom-rear-right perspective view thereof;
FIG. 5 is a front elevational view thereof;
FIG. 6 is a rear elevational view thereof;
FIG. 7 is a top plan view thereof;
FIG. 8 is a bottom plan view thereof;
FIG. 9 is a right elevational view thereof; and,
FIG. 10 is a left elevational view thereof.
The broken lines showing internal components in FIGS. 1, 2, and 5, and the broken lines showing a cable end in FIGS. 1-8 and 10 are included for the purpose of illustrating environmental structure and form no part of the claimed design.

1 Claim, 10 Drawing Sheets
